Primary Examiner — Kevin K Rudzinski(74) *Attorney, Agent, or Firm* — Sughrue Mion, PLLC(57) **CLAIM**

The ornamental design for a polo shirt with collar, as shown and described.

DESCRIPTION

FIG. 1 is a perspective view of a polo shirt with collar showing my new design;

FIG. 2 is a front elevational view thereof;

FIG. 3 is a rear elevational view thereof;

FIG. 4 is a left side elevational view thereof;

FIG. 5 is a detailed view of a cuff thereof; and,

FIG. 6 is a detailed front view of a collar thereof.

The labels and wording are shown in broken lines in FIGS. 1-4 and 6 for illustrative purposes only as the labels and wording form no part of the claimed design.

1 Claim, 6 Drawing Sheets(56)
